UNITED STATES PATENT OFFICE.

KASPER WILT, OF CHICAGO, ILLINOIS.

REFRIGERATOR.

SPECIFICATION forming part of Letters Patent No. 629,143, dated July 18, 1899.

Application filed December 27, 1898. Serial No. 700,317. (No model.)

To all whom it may concern:

Be it known that I, KASPER WILT, a citizen of the United States, residing at Chicago, in the county of Cook and State of Illinois, have 5 invented certain new and useful Improvements in Refrigerators; and I do hereby declare the following to be a full, clear, and exact description of the invention, such as will enable others skilled in the art to which it appertains to make and use the same.

My invention relates to a novel construction in a refrigerator, the object being to provide a device of this character in which low temperature is maintained by the use of cooling mediums other than ice; and it consists in 15 the features of construction and combinations of parts hereinafter fully described and claimed.

In the accompanying drawings, illustrating 20 my invention, Figure 1 is a top plan view of a refrigerator constructed in accordance with my invention, the outer covering being removed and the inner covering partially broken away. Fig. 2 is a sectional view of same on the line 2 2 of Fig. 1. Fig. 3 is a sectional view on the line 3 3 of Fig. 1. Fig. 4 is a sectional view on the line 4 4 of Fig. 3. Fig. 5 is a sectional view on the line 5 5 of Figs. 1 and 3. Fig. 6 is a sectional view on the line 30 6 6 of Figs. 1 and 3. Fig. 7 is a sectional view on the line 7 7 of Fig. 4.

My device consists of a casing A, having double walls B and C, provided with a space between them. Said casing is open at one 35 side and forms a receptacle D to receive the matter to be kept cool. The bottom E consists of a single plate, while the three side walls are provided with a space between them. The inner walls C do not extend as high as 40 the walls D, and thereby a large space F is provided in the upper end of said casing, which is closed by means of a removable cover G. In said space F, I provide a receptacle 1, adapted to receive a vessel 2, containing 45 a heat-absorbing chemical composition. Said receptacle 1 is lined internally with a layer 3 of non-conducting material, the object of which is to prevent too rapid absorption of heat. Said receptacle 1 is adapted to 50 be closed by means of a water-tight cover 4. I also provide a covered receptacle 5 in said space F, which connects at one side with a

pipe 6, entering the space D at its upper end. At an adjacent side said receptacle 5 connects with another pipe 7, also entering said 55 space D at its upper end, but at a point distant from the point of communication of pipe 6 therewith. An electric fan - motor 8 is mounted in said receptacle 5 and is adapted to draw air through said pipe 6 and discharge 60 it into pipe 7, thereby creating a rapid circulation in said space D. A pipe 9 passing through said space F connects chamber D with the outer air for purposes of ventilation. The space between the double walls B and C 65 is connected at the lower rear end with a water-supply pipe 10, extending some distance up into said space, and likewise said space is provided with an opening 11, through which the water can be drained off. Water is fed 70 to said space continuously and remains normally level with the upper end of an overflow-pipe 12, the lower end of which projects from the bottom of said space between said walls B and C. Said casing A consists, preferably, 75 of metal and is adapted to be mounted in a wooden casing 13, adapted to stiffen and support said metallic casing. The latter is secured in said casing 13 by means of bolts 14 passing through the sleeves 15 and 16, mounted upon the inner wall C and extending to a point adjacent the outer wall B and the cover G. Said sleeves 15 and 16 are surrounded by rubber sleeves 17 of greater length, so that when the bolts 14 passing through said sleeves 85 and corresponding openings in the walls are drawn tight said rubber sleeves are compressed against said walls at their ends, thus forming water-tight joints around said openings. Bracing-plates 18 are preferably slipped 90 over the inner ends of the bolts and forced against the inner faces of the wall C, thereby reinforcing said wall. The cover of said outer casing is provided with an opening 19, covered with gauze, which is adapted to register with said ventilating-pipe 9, said gauze serving to prevent entrance of undesirable matter into the chamber D. A door 20 is also provided in said outer casing and is adapted to control the open end of the chamber D. 100

The operation of my device is very simple. The circulation of cold water through the spaces between the walls and in the space F obviously serves to cool the air contained in

chamber D, and such cooling is further promoted by the circulation of the air caused by the operation of said fan. The heat-absorbing substance contained in said receptacle 1 also serves to absorb heat from both the water and air contained in the device, and thus I produce a very low temperature.

I claim as my invention—

In a device of the kind specified, a cold-air chamber, surrounded on three sides and top by a water-chamber, a water-inlet to said water-chamber, an overflow-pipe, a water-outlet pipe, a receptacle in the upper part of said water-chamber adapted to contain a heat-absorbing substance, a lining of non-conducting material for said receptacle, a chamber containing devices for agitating and causing circulation of air, pipes connecting said chamber with said cold-air chamber, a ventilating-

pipe connecting said cold-air chamber with the outer air, an outer casing adapted to receive said device which is adapted to be secured and supported therein by means of bolts passing through said double walls and through sleeves secured to one of said walls around the openings therein and terminating at a point adjacent the other wall, rubber sleeves of greater length than said first-named sleeves surrounding the latter and adapted to be compressed against said walls by drawing said bolts tight, whereby water-tight joints are formed, substantially as described.

In testimony whereof I affix my signature in presence of two witnesses.

KASPER WILT.
